UNITED STATES PATENT OFFICE.

ARTHUR W. SMITH, OF NEW YORK, N. Y., ASSIGNOR TO YOST WRITING MACHINE COMPANY,
OF ILLION, NEW YORK, A CORPORATION OF NEW YORK.

TYPE-WRITING MACHINE.

No. 911,275.

Specification of Letters Patent.

Patented Feb. 2, 1909.

Application filed December 1, 1905. Serial No. 289,790.

To all whom it may concern:

Be it known that I, ARTHUR W. SMITH, a citizen of the United States, and resident of the borough of Manhattan, city of New York, in the county of New York and State of New York, have invented certain new and useful Improvements in Type-Writing Machines, of which the following is a specification.

10 My invention relates to typewriting machines and more especially to the line spacing mechanism of such machines.

The main object of my invention is to provide a simplified and improved construction 15 of the character specified.

To the above and other ends the invention consists in the features of construction, combinations of devices and arrangements of parts hereinafter explained and particularly 20 pointed out in the claims.

In the accompanying drawings, Figure 1 is a fragmentary top plan view of a platen and its mounting, and showing my improved line spacing devices applied thereto. Fig. 2 25 is a side elevation of the parts shown in Fig. 1 with the platen finger-wheel removed. Fig. 3 is a fragmentary front elevation of the platen and its line spacing mechanism. Fig. 4 is an enlarged perspective view of 30 the adjustable stop for the line spacing pawl and showing the support for said stop. Figs. 5 and 6 are enlarged detail end elevations and sections respectively of the adjustable stop for the line spacing pawl and 35 showing the mounting of the same. Fig. 7 is a fragmentary top plan view of the platen and its line spacing mechanism, the parts being shown as they appear when the line spacing pawl has just engaged with the line 40 spacing ratchet wheel. Fig. 8 is a view corresponding with Fig. 7 and showing the line spacing pawl at the completion of the line spacing movement and co-operating with the line spacing stop. Fig. 9 is a view corresponding to Fig. 8 but showing the adjustable line spacing stop set differently. Fig. 45 45 is a view corresponding with Fig. 8 but showing the adjustable line spacing stop set differently from the ways in which it is set 50 in Figs. 8 and 9.

In the drawings, 1 represents the frame of the machine supporting roller bearings 2 with which engage guide bars 3 secured on a carriage truck 4. A platen carrier 5 is 55 mounted in said truck 4, said platen carrier

providing bearings for a platen axle 6 which supports a cylindrical rotary platen 7. Operatively connected with one end of said platen is a line spacing ratchet wheel 8 provided with peripheral teeth 9 and crown teeth 10. Arranged below the ratchet wheel and co-operative with the peripheral teeth 9 is a detent roller 11 journaled in a spring arm 12 secured by a screw 13 to the platen carrier. 65

The side of the platen carrier 5 adjacent to the ratchet wheel 8 terminates in an arm 14 which extends forwardly beyond the platen and near its end is curved or off-set inwardly as clearly appears in Fig. 1. A 70 forwardly extending line spacing lever 15 is bifurcated or forked at its inner end, the arms 16 and 17 of the bifurcated portion embracing the end of the arm 14 which end is enlarged and formed with a vertical hole 75 which serves as a journal or bearing for a pivot screw 18. The screw 18 passes through an opening in the arm 17 down through the hole in the arm 14 and at its lower end is provided with threads which engage a 80 threaded opening in the arm 16 of the line spacing lever. The forward end of the line spacing lever 15 is provided with a finger portion 19. The upper arm 17 of the lever 15 overhangs the lower arm 16 and is cut 85 away or bifurcated at 20 to provide upper and lower walls or arms 17 which receive between them the pivot end of a line spacing pawl 21. A pivot screw 22 passes downwardly through openings in the upper wall 17 and in the pawl 21, and its lower end which is threaded is received in the threaded opening of the lower wall 17. The pawl 21 projects rearwardly from its pivot 22 and is provided near its rear end with a pin or lug 23 which depends from its under side. A coiled detachable spring 24 lies beneath the pawl 21 and has its rear end secured to the pin 23 and its forward end to a pin or lug 25 extending upwardly from the arm 14. 90 The spring 24 serves normally to maintain the pawl 21 in contact with the inner face of the slot or cut away 20 as clearly appears in Fig. 7 and to maintain the lever 15 against a stop face 26 at the end of the arm 14. The 95 normal positions of the pawl 21 and the lever 15 are best shown in Fig. 1, wherein it will be noted that the working end of the pawl stands some distance away from the crown teeth 10 of the ratchet wheel 8 with 100 105 110

which teeth said pawl is adapted to coöperate when the lever 15 is actuated.

Above the platen axle 6 the side of the platen frame 5 is provided with an upwardly extending arm 5^a which arm is formed with a threaded opening which receives an externally threaded bearing sleeve 27. The bearing opening in the sleeve 27 receives the shaft 29 of a rotary stop member, the inner end of said shaft being provided with a plurality of sloping stop faces or portions 30, 31 and 32, which are at different distances from the pivotal axes of the shaft 29. The sides of the portion 30 extends slightly beyond the sides of the other stop portions as indicated at 30^a for a purpose presently to be described. The outer end of the shaft 29 is reduced as indicated at 29^a, the reduced portion receiving a polygonal finger piece 33, the faces of which are provided with numerals to indicate the corresponding stop faces at the other end of the shaft. Thus, when the numeral "1" is uppermost as shown in Fig. 1, the stop face that affords only a single tooth space of the platen will be presented in the operative position whereas, when the numeral "2" is uppermost, the stop face which affords a two tooth space movement of the platen is presented in the operative position and so on. The finger piece 33 is secured to the reduced portion 29^a of the shaft by any suitable means as a pin 34.

It will be noted from an examination of Fig. 6 that the sleeve 27 fits snugly between the inner face of the finger portion 33 and the opposite face of the head formed by the stop portions so that any longitudinal movement of the sleeve will be transmitted to the stop member as a whole. A flat spring 35 is secured to the platen frame in any suitable manner as by a screw 36, and said spring is provided at its free end with a contact portion 35^a which bears against any one of the flat sides of the stop carrier and maintains said stop member or carrier in adjusted position and is adapted to yield sufficiently to permit said stop member to be turned so that one stop face or another of said stop member may be brought into operative position.

The projections 30^a of the stop portion 30 are adapted to engage with the sides of the contact piece 35^a on the free end of the spring 35, as shown in Fig. 5, so as to prevent a continuous turning of the stop member in either direction and so that some one of the stop portions 30, 31 or 32 will at all times be in position to coöperate with the line spacing pawl 21. The construction and arrangement of the parts is clearly shown in Figs. 4, 5 and 6 and it will be understood from an inspection of said figures and from the above description that the stop member 55 may be rotated by means of the finger por-

tion 33 so as to position any one of its stop faces to be engaged by the pawl 21 to limit the movement of said pawl in line spacing direction and that the spring 25 will serve to maintain said stop member in adjusted position. Furthermore, it will be understood that by turning the threaded bearing sleeve 27 in its bearings, the pawl stop member will be given a motion of translation towards or away from the ratchet wheel 7, thereby enabling said stop member to be adjusted through minute distances so that each and all of its stop faces may properly coöperate with the pawl 21. The end of the bearing sleeve 27 contiguous to the finger portion 33 is formed with a hexagonal head 27^a which enables said bearing sleeve to be readily adjusted in the direction of its length.

The operation of the devices above described may be briefly explained. When the finger piece 33 is turned so that the face thereof bearing the numeral "1" is uppermost, the stopping face 30 of the stop device will be in position to coöperate with a cam face 21^a on the pawl 21 as indicated in Figs. 1, 7 and 8. Normally the line spacing lever 15 and pawl 21 are in the positions indicated in Fig. 1, the pawl being held by the spring 24 against the back stop formed by the face 20 of the cut away 20 and the lever 15 being held against its limiting stop 26 also by said spring 24. This normal position of the line spacing lever 15 is indicated in Figs. 7 and 8 by dotted lines. When the finger piece 19 of the line spacing lever is pressed rightward from the dotted line position in Fig. 7 to that represented by the full lines, the lever will be turned about its fulcrum 18, carrying with it the pawl 21 until said pawl engages with the crown teeth 10. Further pressure on the finger piece 19 will cause the pawl to turn the ratchet wheel, and through it the platen, in line spacing direction until the cam face 21^a on said pawl contacts with the limiting face 30 of the limiting stop member as indicated in Fig. 8. In this position the pawl is jammed between the fixed stop member and the engaged teeth of the line spacing ratchet wheel and the cam face 21^a on the pawl or the inclined stop face or both tend to cam the pawl in firmer engagement with the line spacing wheel the greater the pressure applied to the lever and so that it is impossible to inadvertently effect an overthrow of the platen by a violent actuation of the line spacing lever. This is true whether one or another stop face is employed. The parts are so proportioned and arranged that this operation turns the ratchet wheel a distance represented by the space between one tooth 9 and the next succeeding tooth. It will be noted that during this rearward movement from the position represented in Fig. 7 to that represented in Fig. 8 the pawl 21 has 125

been separated a considerable distance from its back stop on the lever 15. When the line space movement has been completed and the lever 15 is released, the force of the restoring 5 spring 24 is exerted to turn the lever 15 and the pawl 21 about their pivots backward to normal position. During the first part of the return movement the pawl is maintained in contact with the ratchet wheel by the 10 spring. As soon as the pawl contacts with its back stop it is swung away from the ratchet wheel and is turned about the pivot 18 along with the lever 15.

When it is desired to turn the platen in 15 line space direction through a distance represented by two teeth of the ratchet wheel, the finger piece 33 is turned until the face bearing the numeral "2" is uppermost, thereby bringing the stop face 31 into position to co-operate with the line spacing pawl. The parts are so proportioned and arranged that when the lever 15 has been pressed from the normal position represented by the dotted lines in Fig. 9 to the full line position in 25 said figure (in which position, it will be noted, the pawl 21 has been brought into contact with the face 31 on the stop member) the platen will have been turned through a double line-space distance represented by two teeth of the line spacing 30 ratchet wheel. The operations of the lever 15, pawl 21 and spring 24 are similar to those hitherto described in connection with Figs. 7 and 8.

When it is desired to rotate the platen in line spacing direction through a triple space, represented by three teeth of the line spacing ratchet wheel, the finger piece 33 is turned until the face bearing the numeral 40 "3" is uppermost, in which position, as will be seen by reference to Fig. 10, the stop face 32 has been brought into position to co-operate with the pawl 21 to limit the movement of the latter in line spacing direction. The parts are so proportioned that in this 45 relation the pawl 21 operates to turn the platen rearwardly through a distance represented by three teeth of the ratchet wheel 8.

It will be seen that by my invention I provide 50 a line space mechanism which is simple and substantial in construction and appearance and certain in operation, and that the direction of movement of the line spacing lever, or the "pull" thereof, is in substantially 55 the same direction as is the pull of the carriage when the latter is returned to begin a new line of writing, so that a single movement of the line spacing lever in one direction may be given to effect a line spacing movement of the platen and to restore 60 the carriage to the right to begin a new line of writing. Furthermore, it will be seen that a line spacing movement of the platen must first be effected and the pawl 65 jammed at the limit of its movement before

the pressure exerted on the line space lever becomes effective to move the carriage to the right, so that a line spacing operation of the lever against the slight pressure of the spring 24 may be effected, when desired, 70 without moving the carriage to the right. It will further be seen that the pivot end of the line spacing pawl is contained within the line spacing lever so that said pawl is housed in said lever, while the journal or 75 bearing of the lever is also contained within or housed in said lever, while the restoring spring 24 is beneath said pawl and for the most part out of sight of the operator. These features of construction conduce to 80 the simple and attractive appearance of the mechanism.

Various changes may be made in the construction and arrangement of different parts within the scope of my invention. 85

What I claim as new and desire to secure by Letters Patent, is:—

1. In a typewriting machine, the combination of a platen frame; a rotary platen therein; a line spacing ratchet wheel operatively connected with said platen; a line spacing lever pivoted on said platen frame; a line spacing pawl on said lever; and a single spring connected directly to said pawl and operative both on said lever and on said pawl to restore them to normal position. 95

2. In a typewriting machine, the combination of a platen carrier; a platen thereon; a line spacing ratchet wheel operatively connected with said platen; a line spacing lever; a line spacing pawl pivotally connected with said lever; a stop for said pawl on said lever; and a spring operative both to turn said pawl on its pivot and to turn said lever on its pivot. 105

3. In a typewriting machine, the combination of a platen frame; a rotary platen therein; a line spacing ratchet wheel operatively connected with said platen; a line spacing lever pivoted on said platen frame; a line spacing pawl pivoted on said lever; a limiting stop on the frame for said lever; a back stop on the lever for said pawl; and a spring adapted both to maintain the pawl against its back stop and the lever against its limiting stop. 110

4. In a typewriting machine, the combination of a platen frame; a rotary platen therein; a line spacing ratchet wheel operatively connected with said platen; a line spacing lever pivoted on said platen frame; a line spacing pawl pivoted on said lever; a limiting stop on the frame for said lever; a back stop on the lever for said pawl; and a restoring spring connected directly to the pawl 125 and adapted to act to turn the pawl about its pivot and to turn the lever about its pivot.

5. In a typewriting machine, the combination of a platen frame; a rotary platen therein; a line spacing ratchet wheel operatively 130

- connected with said platen; a line spacing lever journaled on said platen frame and having a bifurcated portion embracing its journal; and a line spacing pawl, said lever 5 having another bifurcated portion which receives the pivot end of said pawl.
6. In a typewriting machine, the combination of a platen frame; a rotary platen therein; a line spacing ratchet wheel operatively connected with said platen; a line spacing lever journaled on said platen frame, the journal of said lever being housed within said lever; and a line spacing pawl pivoted to said lever, the pivot end of said pawl being housed within said lever.
7. In a typewriting machine, the combination of a platen frame; a rotary platen therein; a line spacing ratchet wheel operatively connected with said platen; a line spacing lever; a line spacing pawl movable by said lever and operative on said ratchet wheel; a stop for limiting the movement of said pawl in feeding direction, said stop being adapted to be given rotary movement to determine 25 the extent of line space feed of the platen, and means for giving said stop a movement of translation so as to adjust it to coöperate properly with said pawl.
8. In a typewriting machine, the combination of a platen frame; a rotary platen therein; a line spacing ratchet wheel operatively connected with said platen; a line spacing lever; a pawl movable by said lever and operative on said ratchet wheel; a stop 35 member for limiting the movement of said pawl in feeding direction, said member being pivotally mounted and having a plurality of stop faces which are adapted to coöperate with said pawl to permit different 40 extents of line space movements of the platen; and means for moving said stop member parallel with its axis of rotation so as to adjust it to coöperate properly with said pawl.
- 45 9. In a typewriting machine, the combination of a platen frame; a rotary platen therein; a line spacing ratchet wheel operatively connected with said platen; a line spacing lever; a pawl movable by said lever 50 and operative on said ratchet wheel; an adjustable bearing sleeve mounted in said platen frame; and a pawl stop rotatable in said bearing sleeve independently thereof and having a plurality of stop faces.
- 55 10. In a typewriting machine, the combination of a platen frame; a rotary platen therein; a line spacing ratchet wheel operatively connected with said platen; a line spacing lever; a line spacing pawl movable 60 by said lever and operative on said ratchet wheel; a bearing sleeve mounted in said platen frame and adjustable in the direction of its length; and a pawl stop rotatable in said bearing sleeve and having a plurality
- of stop faces, said stop being provided with 65 a finger portion and an index.
11. In a typewriting machine, the combination of a platen frame; a rotary platen therein; a line spacing ratchet wheel operatively connected with said platen; a line 70 spacing lever; a pawl movable by said lever and operative on said ratchet wheel; a bearing sleeve threaded in said platen frame; a pawl stop rotatable in said bearing sleeve and having a plurality of stop faces; and a spring member coöperative with said pawl stop to maintain said stop in adjusted position.
12. In a typewriting machine, the combination of a platen frame; a rotary platen 80 therein; a line spacing ratchet wheel operatively connected with said platen; a line spacing lever pivoted on said platen frame; a line spacing pawl pivoted on said lever; a spring connected at one end directly to the line spacing pawl and at the other end to the platen frame, said spring being adapted both to turn said pawl about its pivot and to turn said lever about its pivot; a bearing sleeve mounted in said platen frame; 90 and a pawl stop rotatable in said bearing sleeve and having a plurality of stop faces.
13. In a typewriting machine, the combination of a platen frame; a rotary platen 95 therein; a line spacing ratchet wheel operatively connected with said platen; a line spacing lever journaled on said platen frame, the journal of said lever being housed within said lever; a line spacing pawl pivoted to said lever, the pivot end of said pawl being 100 housed within said lever; a bearing sleeve in said platen frame; and a pawl stop rotatable in said bearing sleeve independently thereof and having a plurality of stop faces.
14. In a typewriting machine, the combination of a platen frame; a rotary platen therein; a line spacing ratchet wheel operatively connected with said platen; a line spacing lever journaled on said platen frame, the journal of said lever being housed within 110 said lever; a line spacing pawl pivoted to said lever, the pivot end of said pawl being housed within said lever; a bearing sleeve threaded in said platen frame and longitudinally adjustable therein; a pawl 115 stop rotatable in said bearing sleeve independently thereof and having a plurality of stop faces; and a spring member coöperating with said pawl stop to maintain it in adjusted position.
15. In a typewriting machine, the combination of a rotary platen; a line space wheel therefor; hand actuated line spacing devices 120 coöperating with the teeth of said line space ratchet wheel; adjustable means coöperating with said line spacing devices to afford a feed of the platen of one or more teeth of the line spacing ratchet wheel according to

adjustment; and separate adjustable means for regulating the coöperative relation between the first mentioned adjustable means and the line spacing devices.

16. In a typewriting machine, the combination of a rotary platen; a line space wheel therefor; a coöperating line spacing pawl; a stop member which coöperates with said pawl for limiting the movement thereof in a line spacing direction and for jamming it into engagement with the teeth of the line space wheel; and means for adjusting said stop member to afford different extents of line space movement, the pawl being adapted to engage at opposite sides with the line space wheel and the stop member.

17. In a typewriting machine, the combination of a rotary platen; a line space wheel therefor; a coöperating line spacing pawl; a stop member which coöperates with said pawl for limiting the movement thereof in a line spacing direction; means for adjusting said stop member to present different stop faces thereof to the action of the pawl to afford different extents of line space movement, and independent adjustable means for altering the normal relation of said stop member with respect to said pawl.

18. In a typewriting machine, the combination of a rotary platen; a toothed line space wheel therefor; a coöperating line space pawl; a stop member between which and the engaged teeth of the line space wheel said pawl when actuated is adapted to be jammed to limit the movement of the pawl and lock the platen against overthrow; and means for adjusting said stop member to afford different extents of line space movement.

19. In a typewriting machine, the combination of a rotary platen; a line space wheel therefor; a stop member; a coöperating line spacing pawl adapted to be jammed between the engaged teeth of the line spacing ratchet

wheel and the stop member and thus limit the movement of the pawl and lock the platen against overthrow; means for adjusting said stop member to afford different extents of line space movement; and a line spacing lever for said pawl and which is pivoted to swing in the direction of the return movement of the carriage when said lever receives its line spacing movement.

20. In a typewriting machine, the combination of a rotary platen; a line space wheel therefor; a coöperating line spacing pawl; a stop member which coöperates with said pawl for limiting the movement thereof in a line spacing direction; means for adjusting said stop member to afford different extents of line space movement, said stop member being provided with marks to indicate the particular stop face presented for coöperation with the pawl.

21. In a typewriting machine, the combination of a rotary platen; a line space wheel therefor; a coöperating line spacing pawl; a stop member which coöperates with said pawl for limiting the movement thereof in a line spacing direction; means for adjusting said stop member to afford different extents of line space movement, said stop member being provided with numbers to indicate the particular stop face presented for coöperation with the pawl, each number corresponding to the number of teeth of the line spacing ratchet which may be turned by the pawl when it co-acts with the stop face indicated by said number.

Signed at the borough of Manhattan, city of New York, in the county of New York, and State of New York this 29th day of November, A. D. 1905.

ARTHUR W. SMITH.
